UNITED STATES PATENT OFFICE.

ALEXANDER W. BEERS, OF BAYONNE, NEW JERSEY.

FOLDING BOX.

1,013,110.

Specification of Letters Patent.

Patented Jan. 2, 1912.

Application filed March 3, 1911. Serial No. 611,995.

To all whom it may concern:

Be it known that I, ALEXANDER W. BEERS, a citizen of the United States, and residing at Bayonne, in the county of Hudson and State of New Jersey, have invented certain new and useful Improvements in Folding Boxes, of which the following is a specification, such as will enable those skilled in the art to which it appertains to make and use the same.

This invention relates to folding or knock-down boxes designed for use by tailors in packing and shipping suits of clothes or other garments or articles; and the object thereof is to provide an improved box of this class composed of pasteboard, cardboard or other fibrous material, and the invention consists of a box of the class specified composed of top and bottom parts, the top part forming the cover of the box and being adapted to receive the bottom part, and both the top and bottom parts being constructed so as to give strength and stability to the complete box, and said top and bottom parts being also adapted to be folded compactly together separately, and to be placed one upon the other when so folded, said top and bottom parts of the box being of approximately the same dimensions when so folded.

The invention is fully disclosed in the following specification, of which the accompanying drawing forms a part, in which the separate parts of my improvement are designated by suitable reference characters in each of the views, and in which:

Figure 1 is a perspective view of the top part of the box;—Fig. 2 a view similar to Fig. 1 but showing the bottom part of the box; Fig. 3 a plan view of the top or body of the top part of the box; Fig. 4 a view similar to Fig. 3 but showing the bottom or body of the bottom part of the box; Fig. 5 is a perspective view of one end of the top of the box showing the same partly folded. Fig. 6 is a view similar to Fig. 5 showing the top completely folded. Fig. 7 is a view similar to Fig. 5 showing one end of the bottom of the box. Fig. 8 is a view similar to Fig. 6, showing one end of the bottom of the box completely folded. Fig. 9 a horizontal section of one end of the complete box; and, Fig. 10 a section on the line 10—10 of Fig. 1.

In the drawing forming part of this specification, I have shown at a , Fig. 1, the

top part of the box. This part of the box comprises a top or body portion a^2 shown separate in Fig. 3, side portions a^3 , and end portions a^4 . The side portions a^3 , in the form of construction shown, are formed of two pieces or strips connected centrally of the sides of the box as shown at a^5 . On the inner sides of the side portions a^3 , so as to reinforce the same at the point of connection are placed rectangular sheets a^6 which are preferably secured to the side portions a^3 by means of mucilage, paste, glue or the like.

Secured to the inner sides of the end portions of the side members a^3 of the top part of the box are rectangular or square locking sheets a^7 . In practice, only the upper outer corners or halves of said sheets are secured to the side portions a^3 as shown at a^8 , this connection being preferably made by means of wire staples, but said connection may be made by means of glue, paste or the like. The lower inner corners or halves a^9 of said sheets are left free so as to enable the different portions of the top part of the box to be folded, as hereinafter described and as shown in Figs. 5 and 6.

From the foregoing description, it will be seen that those parts of the sheets a^7 which are secured to the sides a^3 of the top part of the box are triangular in form, while the parts a^9 which are left free are also triangular in form. The side portions a^3 are provided with corresponding diagonal score or folding lines a^{10} . In the center of the opposite sides of the top of the box are cut oblong recesses a^{11} and in its ends similar recesses a^{12} . When the top is set up for use as shown in Fig. 1, the lower edges of the reinforcing sheets a^7 at the central portions of the side parts a^3 enter the recesses a^{11} , while the bottom edges of the sheets a^7 enter the recesses a^{12} . This strengthens the top part of the box and serves to hold the side and end portions a^3 and a^4 thereof in an upright position. The bottom outer corners of the sheets a^9 are beveled or cut off at an angle as shown at a^{13} in Fig. 1, and this also facilitates the folding of the members of the top part of the box.

The side and end strips a^3 and a^4 of the top part of the box are secured to the top or body a^2 thereof by binding strips a^{14} of fibrous material, and the top or body a^2 fits within the side parts or portions a^3 and end parts or portions a^4 . The vertical di-

5 incisions of the reinforcing and locking sheets a^7 are slightly greater than the depth of the top part of the box and this enables said reinforcing and locking sheets a^7 to slide over and enter the recesses a^{12} in the 10 top or body a^2 of the top of the box as hereinbefore described and operated as locks for holding the separate portions of the top of the box in position for use. In Fig. 2 I have 15 shown the bottom of the box, which is similar in construction to the top. The same exponents with the letter b are employed in designating the parts of the bottom as are employed with the letter a in designating 20 the parts of the top. This difference, however, is to be noted, the reinforcing and locking sheets b^7 are secured to the ends or shorter sides of the box, and the recesses b^{12} are formed in the ends instead of the sides 25 of the bottom of the box. The diagonal score lines for folding this part of the box are also in the ends or short sides.

30 In Figs. 5 to 8 I have illustrated the collapsing of the box. As will be seen the 25 scored sides are first folded inward, the triangular portions folding outward, and the unscored sides then turned inward without bending to the folded position.

35 Although I have shown the sides and ends 30 of the top and bottom of the box as formed of two strips, connected in the center of sides, it will be understood that this construction is not essential, and the side and end members or strips of both the top and bottom parts of the box may consist of a single member or strip, the end portions of which may be connected at one side, or centrally of one end, or at any suitable point, and other changes in and modifications of 40 these features of the construction may be made as will be readily understood, but in all cases I prefer to use the central reinforcing sheets a^8 and b^8 at the opposite sides of the separate parts of the box for the reason that they reinforce the box at its weakest points and at the point where a cord or other device is usually passed around the box in the operation of tying the separate parts thereof together. By having the recesses a^{12} and b^{12} on different sides of the 45 top and bottom of the box, the reinforcing sheets a^8 assist in maintaining the sides of the bottom in upright position and the reinforcing sheets b^8 assist in maintaining the 50 ends of the top in a vertical position when the two parts are assembled to form the complete box.

55 It is to be noted that when the top of the boxes are folded, the ends of the same have not been bent or folded and are the uppermost parts of the collapsed structure, and that when the bottoms of the boxes are folded the sides in a like condition are the uppermost parts of the collapsed bottoms. 60 By constructing the top and bottom of the

box in this manner the collapsed parts are bundled or packed in a more secure and advantageous manner than would otherwise be the case.

65 After the boxes have been folded, packed and transported to the place where they are to be used, on setting them up, the sides scored and bent in folding or collapsing have a tendency to return to folded condition. This tendency is resisted by the reinforcing and locking sheets a^7 and b^7 . It is, however, found in practice, that by having the scoring and folding in different sides in the bottom and top, aids materially in securing one of the results desired, a symmetrically appearing box. In the bottom of the box, as the ends are scored and folded while the sides remain straight, on the setting up of the bottom, the ends alone have the tendency to fold inward. This tendency is resisted by the locking sheets b^7 . They may not, however, entirely prevent an inward inclination of the ends. The sides will be only slightly affected. On placing the top in its proper position over the bottom, the sides of the bottom prevent any perceptible inward movement of the sides of the top, and the ends of the top not having been folded form straight ends for the completed box. This is found especially 95 desirable in cases where the contents do not entirely fill the box.

70 From the foregoing description and on examination of Fig. 9 of the drawing, it will be seen that the corners of the box 100 when in use are reinforced, both on the ends and sides, by the sheets a^7 and b^7 and the corners of the box are made of three thicknesses, the side portions of the box or the separate parts thereof being also reinforced 105 by the sheets a^8 and b^8 changes in and modifications of the construction herein described may be made, within the scope of the appended claims, without departing from the spirit of my invention or sacrificing its advantages.

75 Having fully described my invention, what I claim as new and desire to secure by Letters Patent, is:—

80 1. A folding or collapsible box, comprising top and bottom parts, each consisting of a main body of flat material, having its edges recessed at its ends or sides, strip portions forming the vertical portions of the parts, hinged to the main body, a part of 115 said vertical portions being scored from the corners of their hinged edges inclining toward the center of the free edges and locking pieces secured to said scored portions between the corners and the scored lines, and extending inward over the scored lines, 120 said locking pieces being of greater vertical extent than the vertical portions to which they are attached and adapted to engage the recesses of the main body.

2. A folding or collapsible box, comprising top and bottom parts each consisting of a main body of flat material, the top body having each of its side edges recessed near 5 its ends, and the bottom body having its end edges recessed in like manner, strip portions hinged to the main body and forming the sides and ends of the said parts, the sides of the top being scored from the corners of their hinged edges toward their free 10 edges in a direction inclining toward the center, and the ends of the bottom part being scored in a like manner, and locking pieces secured to the scored portions be-

tween the score lines and the corner and 15 extending inward over the score lines, said locking pieces being of greater vertical extent than the portions to which they are attached and adapted to engage the recesses of the main body. 20

In testimony that I claim the foregoing as my invention I have signed my name in presence of the subscribing witnesses this 1st day of March, 1911.
